SOLID FUEL STOKING MECHANISM

Cortice H. Hall, Birmingham, Mich., assignor to
 The Timken-Detroit Axle Company, Detroit,
 Mich., a corporation of Ohio

Application February 27, 1946, Serial No. 650,476

13 Claims. (Cl. 198—103)

1

This invention relates to devices for conveying solid fuel such as coal from a fuel bin to a furnace or burner and more particularly to devices of this general type which are adapted for use with solid fuel burners of the household or domestic type.

The problem is to mechanically transfer solid fuel from the bin to the furnace while maintaining the fuel in its original shape or size, that is, without comminution and degrading, so that it maintains its most efficient size for efficient combustion.

In the past the general practice has been to manually transfer fuel from the bin to a large hopper from where it is automatically fed to a coal burner, usually by a feed screw mechanism. There have been installations where the fuel has been mechanically transferred from the bin to the burner or to the aforesaid hopper, but these installations generally use a conventional feed screw which inherently comminutes the fuel, the degree of comminution and degradation being related to the length of the feed screw from the bin to the hopper. For this reason it is essential that the length of the feed screw be held to a minimum. Another objection of the screw type of bin pick-up is that it forces the coal towards the front of the bin.

The fuel pick-up of this invention will convey all of the coal exposed to any part of the chain without piling it up. Furthermore it travels under a heavy or a deep pile of coal as easily as under a light or shallow pile, with a resulting conservation of power. While it would be desirable to dispense with the feed screw from the hopper to the furnace or burner this has to this date been found impractical in burners of the underfeed type.

Therefore the primary object of this invention is to provide an improved device to transmit solid fuel such as coal from a fuel bin to a furnace or burner, while maintaining degradation and comminution at a minimum.

Another object of the invention is to provide an inexpensive and efficient solid fuel transfer mechanism comprising in novel combination a conveyor for transferring solid fuel from a bin to a hopper from which another conveyor delivers the fuel to the burner, together with a drive for the conveyors.

Another object is the provision of a novel drive head mechanism for transferring solid fuel from an initial conveyor which holds degradation and comminution to a minimum to a conventional screw type conveyor necessary to main-

2

tain the pressure to lift the fuel into a burner, the transferring mechanism also driving the initial conveyor.

It is another object to provide novel gear mechanisms for driving the two conveyors from a single power source, including a device permitting the continued operation of the screw type conveyor if the initial conveyor is out of order.

Still another important object is the provision of a novel fuel pick up mechanism to be disposed in a fuel bin.

Another important object is the provision of a novel link conveyor tube assembly which is readily disassembled for inspection or servicing of the link conveyor and which is designed for flexibility in length for ease in installation.

A still further object is to provide a novel combined conveyor tube support and securing clamp.

Another object is the provision of a novel adjustable resilient means to prevent a link type conveyor from buckling and to take up the slack resulting from normal wear and stress.

Still other objects of the invention will become apparent as the description proceeds in connection with the drawings wherein:

Figure 1 is a top plan view of the entire mechanism.

Figure 2 is a side elevation of the entire mechanism shown in Figure 1.

Figure 3 is a sectional view substantially along line 3—3 of Figure 2, with details not in the plane of the section omitted.

Figure 4 is a top plan view, partly in section, of the gears for driving the link and feed screw conveyor.

Figure 5 is a sectional view substantially along line 5—5 of Figure 4, looking in the direction of the arrows.

Figure 6 is a vertical sectional view through the link conveyor bin feed drive head and gear housing.

Figure 7 is a view looking in the direction indicated by line 7—7 of Figure 6 with parts broken away to show the link conveyor bin feed drive head.

Figure 8 is a vertical sectional view substantially along line 8—8 of Figure 1, looking in the direction of the arrows, and showing a fastening and support bracket.

Figure 8a is a vertical sectional view showing a fastening similar to that of Figure 8 but without a support bracket.

Figure 9 is a vertical sectional view substantially along line 9—9 of Figure 1, looking in the

direction of the arrows and showing a coupling for joining the abutting ends of lengths of the conveyor tube.

Figure 10 is a vertical sectional view substantially along line 10—10 of Figure 1, looking in the direction of the arrows.

Figure 11 is a vertical sectional view substantially along line 11—11 of Figure 1 and looking in the direction of the arrows.

Figure 12 is a top plan view of the fuel pick-up mechanism.

Figure 13 is a side elevation view of the fuel pick-up mechanism of Figure 12, partly in section.

Figure 14 is a vertical sectional view substantially along line 14—14 of Figure 12 omitting details of the sprocket and conveyor chain but showing the slots 182 and 183 in the fuel pick-up mechanism housing.

As shown in Figures 1 and 2, the mechanism comprises as principal elements a fuel pick-up mechanism 1, a link type conveyor tube assembly 2, a bin-feed drive head and transfer device 3, a link conveyor drive gear box 4, a feed screw drive gear box 5, hopper 6, and motor 7. Besides driving the link and feed screw conveyor gear boxes 4 and 5 through a belt 8, the motor drives a fan 9 furnishing air to a burner or furnace 10 which receives its fuel from the hopper 6 via a tube 11 having a feed screw conveyor 12 therein. Air from the fan 9 passes through a duct 13 to the burner 10. The fan 9, burner 10 and duct 13 do not form any part of the invention.

The hopper 6 is generally rectangular in plan, fabricated of sheet metal. Vertical front and rear panels 15 and 16 are joined by a center portion 17 (see Figure 3) which forms a longitudinal trough in the bottom of which is disposed the screw conveyor 12. A cover plate 18 closes the top of the hopper and overlaps it as shown in Figure 1 to provide a support for the bin-feed drive head and transfer device 3. The motor 7 is also supported by cover plate 18. The front and rear panels 15 and 16, the center portion 17, and the cover plate 18 are welded together. The panels 15 and 16 are provided with openings through which the feed screw 12 extends from the feed screw drive gear box 5, which is mounted on the rear panel 16, to the furnace 10.

On the front panel 15 a clean out assembly 19 (Figure 2) is mounted, having a removable section 20 held in place as by wing nuts 21. The cover plate 18 includes a removable section 22 adjacent the front panel 15 to provide access to the interior of the hopper, and normally held in place by conventional means such as bolts. The fan 9 is carried by a bracket 23 which is welded to the center portion 17 of the hopper.

The bin-feed drive head and transfer device 3 comprises an upper case 24 which rests upon and is fastened to a mating lower case 25 by means of bolts 26. The outer wall of the lower case 25 is substantially cylindrical and perpendicular to the horizontal cover plate 18 upon which it rests. The top edge of case 25 lies in a plane which is inclined to the horizontal as best seen in Figures 2 and 6, so that the upper case 24 resting upon it is similarly inclined. Cast integrally with the lower case 25 is a central guide and support 27 having a central vertical bore 30 through which passes a power take-off shaft 28 (Figure 6).

A sprocket support member or yoke 29 (Figures 6 and 7) bridges the top of the lower case 25, and is secured thereto by screws 32. The yoke 29

29 has a central opening which accommodates a bearing cage assembly 33 fastened to the yoke by screws 34. Journalled in the bearings in the bearing cage assembly 33 is a shaft 35 to which is keyed or otherwise fixed a combined gear and sprocket member 36. The axis of shaft 35 is perpendicular to the plane of the inclined top edge of the case 25, and intersects the axis of the power take-off shaft 28. An adjustment nut 37 on the upper end of shaft 35 secures the shaft in position and provides adjusting means for a pair of tapered roller bearings 38 and 39 in the bearing cage assembly. A lock washer 40 and nut 42 lock the adjustment nut 37 in position on shaft 35.

The gear and sprocket member 36 has fixed to its lower face a bevel face gear 43 which meshes with a bevel face gear 44 splined on the upper end of the power take-off shaft 28 so that the shaft 28 drives the gear and sprocket member. The bottom of the gear 44 abuts the top of an internal shoulder 45 of the guide and support 27. The top of the support 27 is inclined parallel to the sprocket 36 and bears against a seal 46 which is seated in a groove in the bottom of the sprocket. A similar seal 47 on the top of the sprocket 36 engages the bottom of an annular wall 48 depending from the yoke 29 and surrounding the bearing cage assembly 33, and a third seal 50 is clamped between the upper case 24 and the yoke 29. Seals 46, 47 and 50 prevent the entrance of dirt or coal into the bearings and gears.

The upper end of the conveyor tube assembly 2 connects to the drive head and transfer device 3 by inserting the free end of the tube assembly into recesses 49 formed in the outer ends of the tubular extension 52 (Fig. 7) and 53 (Figs. 6 and 7) on the drive head 3. Bolts 54 when tightened, clamp the conveyor tube assembly 2 between the extensions 52 and 53 on upper and lower cases 24 and 25. The tubular extensions 52 and 53 lie in the same plane as the gear and the sprocket 36 and both the tubular extensions and the upper and lower cases 24 and 25 are dimensioned to provide for the passage of a link conveyor 55 into the drive head 3 via the extension 53, around the sprocket 36 and thence back into the conveyor tube assembly 2 via the extension 52. The conveyor 55 is preferably of the type disclosed in my application filed August 31, 1944, Serial No. 552,920 for "Chain Conveyor," of which the present is a continuation-in-part and which issued September 9, 1947 as United States Letters Patent No. 2,426,998. The conveyor engages recesses in the periphery of the upper and lower spaced flanges 61 and 62 and on the sprocket and is driven thereby.

The sprocket rotates counterclockwise when viewed as in Figure 7 and coal carried through the extension 53 enters the drive head and transfer device 3 and is released by the flights 57 on the conveyor 55 due to the lower level of the floor 57a of the drive head and transfer device 3 and the inclination of the sprocket 36. Teeth 66 are formed on the sprocket 36 by means of aligned spaced recesses in the flanges 61 and 62. Each sprocket tooth on the lower flange 62 of the sprocket member 36 is provided with a downwardly depending blade 58 for the purpose of raking coal or other solid fuel along the floor of the bin feed drive head and transfer device 3 to an opening 59 in the floor which is disposed directly over an opening 60 (Figures 1 and 6) through the cover plate 18, the coal thus being discharged into the hopper 6.

5

On the bottom of the lower case 25 of the bin feed drive head and transfer device is provided an outwardly extending continuous flange 63. The flange 63 is engaged by several equally spaced clamps 64 which clamp the lower case 25 to the top of the cover plate 18 by means of bolts 65. By loosening the bolts 65 the entire bin feed head 3 can be rotated about the axis of the power take-off shaft 28 and secured in any one of an infinite number of positions about an arc so that the fuel pick-up mechanism 1 may be accurately placed in the fuel bin regardless of the relation of the position of the fuel bin to the heating plant. The opening 60 in the cover plate 18 through which the coal enters the hopper should thus have a greater arcuate length than the opening 59 through the floor of the lower case 25 so that the coal can fall into the hopper irrespective of the angular position of the bin feed drive head 3.

The bin feed drive head 3 is driven by the motor 7 through the belt 8 and two separate gear boxes 5 and 4 previously mentioned as the feed screw drive gear box 5 and the link conveyor drive gear box 4.

The gear box 5 which is mounted on the rear side of panel 16 comprises two sections which may be designated as the input section 71 and the output section 72 having cooperating, locating and securing flanges 73 and 74 through which pass bolts 75 for securing the two sections together. At the forward end of the output section is a throat 76 which is provided with an enlarged cylindrical portion 77 having openings aligned with openings in the panel 16 for the passage of bolts 78 which secure the gear box 5 to the panel 16. A pulley 79 which is driven by the belt 8 is fixedly attached to the outer end of a power input shaft 82 (Fig. 5) which is journaled at its outer end in a roller bearing cage assembly 83 secured by screws 84 to a protruding hollow boss 85 on the input section 71 and containing a dirt and oil seal 81. The inner end of shaft 82 is journaled in a boss 86. Integral with the shaft 82 is a worm 87 which drives a worm wheel 88 mounted for rotation on and with respect to a feed screw drive shaft 89.

The drive shaft 89 has one end journaled in a roller bearing 92 in the input section 71 and its other or forward end portion journaled in a roller bearing 93 in the throat 76 of the output section 72. The forward end of shaft 89 projects into the enlarged cylindrical portion 77 and is squared at 94 for driving engagement with a mating socket in the rear end of the feed screw conveyor 12 (not shown in Figure 4). A seal and baffle 95 in the throat 76 prevents the entrance of dirt into the bearing 93 and gear box 5 and the loss of lubricant from the gear box. On the other end of the shaft 89 a lock nut and washer assembly 96 provides means for adjusting bearings 92 and 93, there being a removable sealing cap 97 on the input section 71 by which access to the assembly 96 is obtained.

A spur pinion 98 is integral with the worm wheel 88 and has driving engagement with a spur gear 99 keyed for rotation with a countershaft 102 lying in the same horizontal plane as shaft 89 and which is journaled at one end in a bearing 103 in the input section 71 and adjacent its other end in a bearing 104 in the output section 72. Integral with the spur gear 99 is a spur pinion 105 having a driving engagement with a spur gear 106 mounted on the feed screw drive shaft 89 and keyed thereto for rotation there-

6

with. Thus the gear box 5 provides a reduction gear whereby the worm 12 is driven at a low speed from the pulley 79.

Power to the link conveyor drive gear box 4 is furnished by the gear box 5 through the countershaft 102 which projects through the wall of the output section 72 of gear box 5, there being a dirt and oil seal 107 between shaft 102 and the wall. The gear box 4 includes a lower cup-shaped section 108 (Fig. 6) having an integral outer bracket 109 into which bolts 112 are threaded to fasten the section 108 to the front of panel 16. The top of the section 108 is closed by an upper section 113 which is fastened to section 108 by cap screws 114, and includes an upwardly extending integral tube 115 and a downwardly extending pilot flange 116 which extends into a mating recess in the top of 108 to align the two sections.

The upper end of the integral tube 115 passes through the cover plate 18 and has a mating engagement with the central bore 30 in the guide and support 27 of the lower case 25, there being a seal 118 between the tube 115 and the wall of the bore.

As shown in Figure 4 the cup-shaped section 108 has a protruding hollow boss 119 having a horizontal rotary input shaft 122 journaled for rotation in spaced bearing assemblies 123 and 124. The shaft 122 passes through the bearing assembly 123 which is fastened to the boss 119 by cap screws 125 and includes a dirt and oil seal 126. The other bearing assembly 124 is retained against its seat in the boss 119 by the threaded plug 127.

Integral with the input shaft 122 is a worm 128 having driving engagement with a worm wheel 129 keyed to the power take off shaft 28. The lower end of the shaft 28 is journaled in a bushing 132 in the lower section 108 and its upper end, below the bevel gear 44, is journaled in a bushing 133 in the tube 115. The worm wheel 129 rides on a thrust bearing 134.

Power from the countershaft 102 of the gear box 5 is transmitted to the axially aligned input shaft 122 of the gear box 4 by means of a tubular coupling 135 which is secured to the countershaft 102 by a tapered pin 136 and to the input shaft 122 by means of a shear pin 137.

The conveyor tube assembly generally indicated at 2 extends from the fuel pick up mechanism 1 to the bin feed drive head 3. The conveyor tube itself is formed of two similar stampings 138 and 139 (best shown in Figures 8 and 8a), each having two substantially semi-cylindrical portions 142 and 143 connected by an integral web 144. The portion 143 of each stamping is provided with an offset flange 145 extending longitudinally of the stamping which provides a seat and overlapping flap for the mating part of the portion 142 of the other stamping when the stampings are placed face to face to form parallel tubes as shown. The stampings 138 and 139 are held in assembled relationship as shown in Figure 8a by means of bolts 146 which pass through aligned openings in the webs 144 and also pass through yokes 147 and 148 above and below the webs. The yokes 147 and 148 are of such length that they engage the spaced semi-cylindrical portions 143 and by means of the bolts 146 and cooperating nuts 149 they clamp the stampings together. Fastenings of this type are located at substantially equally spaced distances along each length of tubing to hold the stampings together. At other spaced

70
75

intervals along the length of the assembly 2 the lower yokes 148 and the nuts 149 are replaced by a supporting bracket 152 (Figure 8) to support the tubing above the floor. The top of each bracket 152 is threaded to receive the bolt 146 and is also shaped to conform to the bottom of stamping 139 so that the two stampings are clamped between a bracket 152 and a yoke 147 by a bolt 146. The bracket is fastened to the floor by any suitable means.

The conveyor tube sections formed by the mating stampings 138 and 139 are preferably made in short lengths which are coupled together to obtain the length required in any particular installation. Couplings of the type shown at the left of the section line 9—9 of Figure 1, and also shown in Figure 9 are used to couple together the abutting ends of two lengths of tube sections. These couplings comprise a pair of identical castings 153 and 154 one of which is placed on top of the joint between the abutting tube sections and the other below, the two castings being clamped together with the tube sections clamped between them, by spaced bolts 155 passing through both castings and the web 144 of the tubing. When clamped in this manner the two castings do not touch, as is clear from the drawings, so that the abutting tube sections are adequately clamped between the castings by the bolts 155 and nuts 156. Each casting 153 and 154 has a similar recess indicated at 157 which accommodates the offset flanges 145 of the tube stampings so that the flanges are not deformed by the castings when the coupling is clamped together.

The conveyor tube assembly is horizontal except for a short length which is inclined upwardly to enter the bin feed drive head 3. An angle coupling shown cut by the section line 10—10 of Figure 1, and shown in section in Figure 10, is used to join the horizontal tubing to the inclined tubing. The angle coupling comprises an elbow member casting 158 having parallel passageways 159 and 160 therethrough, which at their ends are in axial alignment with the horizontal and inclined portions of the tube assembly and are also recessed so that inside surfaces of the ends of the tube assembly are flush with the walls of the passageways 159 and 160. Also, as indicated in Figure 2, the top portions of the ends of the casting 158 are cut away so that a pair of coupling castings 163 and 164 may engage the exposed ends of the tube assembly to clamp them against the elbow casting 158. The securing of the tube assembly, the coupling castings, and the elbow member casting is accomplished by means of cap screws 165 and 166 passing through the coupling castings 163 and 164, the webs 144 of the tubing assembly, and threaded into the elbow casting 158. The coupling castings 163 and 164 are identical and are similar to the coupling castings 153 and 154 except that they are of shorter length axially of the tube assembly 2 and have only one bolt passing therethrough as is clearly shown in Figure 1. The ends of the horizontal and inclined portions of the tubes extend into the casting 158 to points substantially under the inner ends of the castings 163 and 164, as indicated by the dotted lines 161 of Figure 2.

The conveyor tube assembly is attached to the base portion of the fuel pick up mechanism 1 by a half cap 167 having an integral yoke 168, and secured to the top of a portion 169, which is integral with a base member 175, by cap screws 75

172 and 173. It is to be particularly noted that the half cap 167 does not extend around the tube portion 142 so that the top of the tube portion may be cut away as shown to provide in combination with an opening 174 in the top of the fuel pick up mechanism 1 an aperture of sufficient length to receive the amount of coal required to load the conveyor tube assembly 1.

The webs 144 of the mating conveyor tube stampings 138 and 139 are perforated at equally spaced points two inches apart along their length for the passage of the bolts 146, 155 etc., which secure the stampings together and to the brackets 152, couplings etc. The length of the links of the conveyor 55 is also two inches, and thus the length of the conveyor tube assembly 2 can be increased or decreased in equal increments of two inches or multiples thereof by simply adding or removing the required number of links from the conveyor and cutting the conveyor tube to length, between two of the said perforations in the webs 144. Thus the distance between bolts 155 of the coupling of Figure 9 is two inches. The length of the conveyor tube assembly 2 can thus be adjusted to meet any given condition. Because of the assembled construction of the assembly 2 it is easy to remove any one or more of the upper stampings 138 to gain access to the conveyor 55 to repair a break therein, while the conveyor remains supported along its whole length, as will be apparent. The assembly 2 having a conveyor of about 15 feet in length has been found to be very efficient in regard to power consumption which is about 1 watt for each foot of length. As the conveyor length is increased the wattage per foot of length will decrease since the greater part of the wattage is consumed by the drive.

The fuel pick-up mechanism generally indicated at 1 is shown in enlarged detail in Figures 12, 13 and 14 and comprises the base member 175 and a mating cover member 176 secured together by conventional means such as bolts 177 extending through openings in cooperating bosses 178 on the base and cover members. Integral legs 179 on the base member 175 supports the pick-up mechanism 1 at the proper level above the floor in alignment with the conveyor tube assembly 2, and bosses 180 are provided thereon through which bolts or the like may pass to secure the base member to the floor.

The base and cover members 175 and 176 are provided with oppositely disposed internal longitudinal slots 182 and 183 which together form a track or guide for a yoke member 184, and the hollow space between the base and cover members adjacent their peripheries provides a conduit for the passage of the link conveyor 55 therethrough. In its passage through the aforesaid hollow space the conveyor 55 passes around a sprocket 185 which is journaled for rotation about a vertical shaft 186 mounted in the spaced arms of the yoke 184 and secured by a pin 187.

Integral with the base member 175 and projecting upwardly on the interior thereof are a pair of spaced bosses 188 and 189. Near their bottoms the bosses 188 and 189 are provided with aligned passageways respectively for a coiled compression spring 192 and a central guide 193 for the spring, integral or affixed to the yoke 184 for longitudinal movement therewith in the guide formed by slots 182 and 183. A protruding hollow boss 194 on the cover member 176 encloses the bosses 188 and 189.

A conveyor tension adjustment screw 195 is

journalled for rotation within the top portions of the bosses 188 and 189 and between the bosses has threaded thereon a yoke 196 for movement axially of the screw as the screw is rotated. The yoke 196 at its other end has a bore through which the compression spring guide 193 passes in sliding engagement. The tension in the link conveyor 55 is adjusted by rotating the adjustment screw thus moving the yoke 196; to the left as viewed in Figure 13 to increase the tension in the link conveyor or to take up slack therein, and to the right to obtain the opposite effect.

As shown in Figure 13 the adjustment screw 195 may be inserted through a coaxial opening 197 through the wall of the boss 194. After insertion, axial movement to the left is prevented by the reduced end of the screw which forms a shoulder 198, and movement to the right is prevented by a collar 199 affixed to the screw by a pin or the like. This is done before the cover member 176 is attached to the base member 175.

An adjustment extension member 202 passing through opening 197 has a keyed engagement with the end of the adjustment screw 195 by a conventional means such as the tongue and groove shown at 203. The extension member 202 is journalled for rotation in the opening 197, and in the half cap 167 and secured against longitudinal movement therein by a cotter pin 204 passing through a peripheral groove in the member. The forward end of the member 202 extends through an aperture in the wall 205 of the coal bin as shown in Figures 1 and 2 and is squared to receive a crank or the like by which means the tension of link conveyor 55 may be adjusted from a position outside of the bin.

The control circuit for motor 7 is closed in any conventional manner as by means of a thermostat. When energized, the motor 7 drives the fan 9, thus blowing air into the furnace 10. Simultaneously the motor, through belt 8 rotates the pulley 79 by which means the gear boxes 5 and 4 are driven to actuate the feed screw conveyor 12 and the link conveyor 55. In the event of the mechanism in the conveyor tube assembly becoming jammed, the shear pin 137 will shear to stop the transmission of power to the gear box 4 which furnishes power to the link conveyor 55. The gear box 5 which drives the feed screw conveyor 12 continues in operation and the hopper 6 may be filled with fuel manually so that the stoker and furnace may be kept in operation.

In normal operation the solid fuel which enters the fuel pick up mechanism 1 through the opening 174 in the top thereof, is conveyed to the conveyor tube assembly 2 which deposits it in the bin feed to drive head 3, where it is picked up by the blades 58 on the sprocket and dropped into the hopper 6 through the opening 60 in the cover plate 18, from where it is delivered to the furnace by screw conveyor 12.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A stoker mechanism for a furnace or retort

comprising a hopper; a screw conveyor delivering solid fuel from said hopper to the furnace; a solid fuel pick up mechanism adapted to be disposed in a bin; a conveyor tube assembly housing an endless conveyor chain for transferring solid fuel from said pick up mechanism to said hopper, said fuel pick up mechanism and said conveyor tube assembly forming a substantially rigid unit; a drive sprocket for said chain mounted in said conveyor tube assembly and a drive shaft mounted on said hopper coupled to said sprocket; and means providing a swivel connection between the conveyor tube assembly and the hopper having means for clamping it in a desired position for disposing said fuel pick up mechanism and said conveyor tube assembly in any of an infinite number of positions about an arc with relation to said hopper.

2. A stoker mechanism for a furnace or retort comprising a hopper; a screw conveyor delivering solid fuel from said hopper to the furnace; a solid fuel pick up mechanism adapted to be disposed in a bin and including an idler sprocket; a bin feed drive and transfer device and including a drive sprocket, said transfer device discharging into said hopper; a conveyor tube assembly connecting said pick up mechanism and said transfer device; and an endless conveyor housed in said tube and passing around said drive and idler sprockets.

3. In the apparatus described in claim 2, a first speed reducing gear box having an input shaft and an output shaft connected to said drive sprocket; and a second speed reducing gear box having an input shaft and two output shafts, one of said output shafts from said second gear box being connected to said screw conveyor and the other of said output shafts being connected to the input shaft of said first gear box; and power means for driving the input shaft of said second gear box.

4. In the apparatus described in claim 2, a first speed reducing gear box having an input shaft and an output shaft connected to said drive sprocket; a second speed reducing gear box having an input shaft and two output shafts, one of said output shafts from said second gear box being connected to said screw conveyor and the other of said output shafts being connected to the input shaft of said first gear box, there being an overload release means in said last mentioned connection; and power means for driving the input shaft of said second gear box.

5. A stoker mechanism for a furnace or retort comprising; a hopper; a screw conveyor delivering solid fuel from said hopper to the furnace; a solid fuel pickup mechanism adapted to be disposed in a bin; a bin feed drive and transfer device, said transfer device discharging into said hopper; a conveyor tube assembly; an endless conveyor housed in said assembly for transferring solid fuel from said pickup mechanism to said transfer device, said endless conveyor passing from said pickup mechanism through a first portion of said conveyor tube assembly to said transfer device thence back through a second portion of said conveyor tube assembly to said pickup mechanism, said first and second portions of said conveyor tube assembly lying in close side by side relation in a substantially horizontal plane whereby said endless conveyor is supported by said assembly, and the upper portion of said first and second portions of said conveyor tube assembly being removable to provide access to said endless conveyor while it remains supported.

6. In a stoker mechanism for a furnace or retort, a hopper, a bin feed drive head and transfer device disposed over said hopper, comprising a hollow lower case member mounted on said hopper with its upper edge in a plane inclined to the horizontal and having a substantially horizontal floor with a discharge opening disposed over said hopper; an upper case member secured to the upper edge of said lower case member; means supporting a shaft for rotation within said case members with its axis normal to the plane of the upper edge of said lower case member; a link conveyor drive sprocket mounted on said shaft; blades carried by said sprocket operable to scrape solid fuel along said floor to said discharge opening; and means for rotating said drive sprocket.

7. The mechanism described in claim 6 wherein said upper and lower case members are provided with complementary extensions forming tubular receptacles for receiving the ends of a conveyor tubular assembly, said extensions being operable to clamp the tube end of the assembly between them.

8. The mechanism described in claim 6 wherein said lower case member has a hollow central coaxial guide and support providing passage for said drive sprocket rotating means; and means operable to secure said case members to the top of said hopper in an infinite number of angular positions about the axis of said lower case member.

9. In the apparatus described in claim 2, said solid fuel pick up mechanism comprising complementary base and cover members forming between them a tubular passage for said endless conveyor; and means forming an opening in at least a portion of the top of said cover member to permit solid fuel to enter said mechanism for removal by said conveyor.

10. In the apparatus described in claim 2, said solid fuel pick up mechanism comprising complementary base and cover members forming between them a tubular passage for said endless conveyor; means forming an opening in a portion of the top of said cover member to permit the entrance of solid fuel into said pick up mechanism; and resilient means operable to shift said sprocket to take up the slack in said conveyor.

11. In the apparatus described in claim 2, said solid fuel pick up mechanism comprising complementary base and cover members forming between them a tubular passage for said endless conveyor; means forming an opening in a portion of the top of said cover member; resilient means operable to shift said sprocket to automatically take up the slack in said conveyor; and means operable from outside the bin to control the force of said resilient means.

5 12. Apparatus for moving solid fuel from a bin wherein a supply of said fuel is piled to a furnace wherein the fuel is to be burned comprising a bin feed pick up device adapted to be placed within said bin beneath the pile of solid fuel and having an apertured top for entry of fuel, a conveyor tube assembly connected at one end to said pick up device, an endless conveyor housed by said conveyor tube assembly and extending through said pick up device at said aperture so as to receive fuel entering said aperture, a relatively short screw feed assembly adapted to be connected to the furnace at its discharge end, and solid fuel transfer means between the adjacent end of said conveyor tube assembly and said screw feed assembly.

10 13. In a solid fuel transfer device disposed between a hopper and a conveyor adapted to discharge into the top of the hopper, a housing mounted on the top of said hopper, a power operated conveyor drive member rotatably mounted in said housing, said housing having an aperture in its lower wall communicating with said hopper, and a scraper blade on said drive member adapted to move coal deposited by said conveyor into said housing toward said aperture for discharge into said hopper.

CORTICE H. HALL.
